UNITED STATES PATENT OFFICE.

CHARLES STUMMA, OF BRANDON, IOWA.

MOTOR-VEHICLE.

No. 822,162.

Specification of Letters Patent.

Patented May 29, 1906.

Application filed August 11, 1905. Serial No. 273,780.

To all whom it may concern:

Be it known that I, CHARLES STUMMA, a citizen of the United States, residing at Brandon, in the county of Buchanan and State of 5 Iowa, have invented a new and useful Motor-Vehicle, of which the following is a specification.

This invention relates to motor-vehicles; and it has particular reference to the driving 10 and the running-gears of this class of vehicles, the objects being to simplify and improve the construction and operation of the same, to facilitate the steering or turning of the machine, and to produce a machine of this class 15 which shall possess superior advantages in point of simplicity, durability, and general efficiency.

With these and other ends in view, which will readily appear as the nature of the invention 20 is better understood, the same consists in the improved construction and novel arrangement and combination of parts, which will be hereinafter fully described, and particularly pointed out in the claims.

25 In the accompanying drawings has been illustrated a simple and preferred form of the invention, it being, however, understood that no limitation is necessarily made to the precise structural details therein exhibited, but 30 that changes, alterations, and modifications within the scope of the invention may be resorted to when desired.

In said drawings, Figure 1 is a top plan view showing the frame and driving-gearing 35 of a motor-vehicle embodying the invention. Fig. 2 is a side elevation of the same. Fig. 3 is a detail front view. Fig. 4 is a sectional detail view taken on the plane indicated by the line 4-4 in Fig. 1.

40 Corresponding parts in the several figures are indicated throughout by similar characters of reference.

The traction-wheels 11 of the improved vehicle are mounted for rotation upon the 45 spindles of an axle 2, extending transversely under the frame 3, which latter has been shown of rectangular shape and provided with cross-pieces 4 and 5 and with a longitudinal brace 6, connecting the front cross- 50 bar 5 with the front member of the frame.

Securely connected with the traction-wheels or with the hubs of said wheels are spur-gears 7, which are driven by pinions 8, mounted upon the outer ends of short shafts 55 9, which are journaled in boxes 10 upon the

side members of the frame, said shafts being provided at their inner ends with bevel-gears 11, which are adapted to be driven by bevel-pinions 12 and 13, said bevel-pinions being feathered or splined upon shafts 14, as 60 by means of splines 15. The shafts 14, which are journaled in bearings upon the cross-bars 4 and 5, are provided at their front ends with bevel-gears 16 and 16^a, meshing with and driven by bevel gear-pinions 17 and 17^a, 65 which are keyed upon shafts 18 and 18^a, which are journaled in axial alignment with each other in boxes or bearings upon the side members of the frame and upon the longitudinal brace member 6, the inner ends of said 70 shafts abutting upon each other, as indicated by dotted lines in Fig. 1 of the drawings. The other ends of the shafts 18 and 18^a carry spur-gears 19, which are formed integrally with band-wheels 20, said combined spur and band wheels being supported loosely upon the respective shafts. Said shafts are provided with cone wheels or pulleys 21, splined thereon and rotatable therewith, said cone-wheels having hubs provided with annular 80 grooves 22, engaged by the forwardly-extending bifurcated arms 23 of bell-crank levers B, fulcrumed upon the frame, the laterally-extending arms 24 of said levers being connected with suitable operating-rods 25, 85 whereby they may be conveniently manipulated to move the cone-pulleys upon their respective shafts.

The combined spur and band wheels are provided upon the rims thereof with friction-faces 26, adapted to be engaged by shoes 27, which are radially-slidable upon the spokes or bodies of the wheels and which are provided at their inner ends with concave members 28, assembled around the cone-pulleys and adapted 90 to be actuated by the latter. Each of the combined spur and band-wheels is equipped with a plurality of—say four—friction-shoes and related parts, including the concave members or segments 28, which latter may be engaged by the cone-pulleys to force the friction-shoes into active engagement with the friction-rims of the combined spur and band wheels.

A transverse shaft 29, supported in bearings upon the side members of the frame, is provided at the ends thereof with pinions 30, meshing with the spur-wheels 19. The shaft 29 has been shown as equipped with a sprocket-wheel 31, adapted to receive motion by means of a link belt from the source of power, which 11

consists of a motor supported upon the frame of the machine, but which has not been shown in the drawings.

Upon the front end of the frame is mounted 5 a heavy clip 32, which is secured in part upon the longitudinal brace 6 and through which a heavy bolt 33 extends into the front member of the frame. Pivotally mounted upon said bolt is a tilting beam 34, between which 10 and the front member of the frame there are interposed washers 35 and wear-plates 36. Through the ends of the beam extend vertical bolts 37, upon which are mounted for rotation sleeves 38, connected with frames 39, 15 in which the front caster-wheels 40 are supported for rotation. It will be readily seen that said caster-wheels will yield to the direction to which the vehicle is steered and that the tilting beam upon which said caster-wheels are supported will readily adapt itself 20 to rough and uneven ground.

Suitably supported upon the side members of the frame are pairs of levers 41 and 42, said levers having bifurcated ends engaging 25 annular grooves 43 and 44 in the hubs of the bevel-pinions 12 and 13, respectively. The outer ends of the shifting-levers 41 and 42 are connected in pairs by means of operating- 30 rods 45, whereby they may be readily manipulated to shift the relative positions of the bevel-pinions 12 and 13.

In operation motion is transmitted from the source of power to the shaft 29, which transmits to the combined spur and band 35 wheels 19 and 20, either or both of which may be utilized when the vehicle is stationary for the purpose of driving machinery of any kind. By manipulating the rods 25 to move the cone-pulleys 21 in an outward direction the 40 friction-shoes will be thrown into engagement with the friction-rims of the combined spur and band wheels, which latter, being thus connected with the shafts 18 and 18^a, will rotate the latter, transmitting motion to 45 the longitudinally-disposed shaft 14. By manipulating the operating-rod 45 to properly adjust the bevel-pinions 12 and 13 motion may be transmitted to the traction-wheels to rotate the latter simultaneously in 50 a forward or rearward direction, according to the direction in which it is desired to drive the vehicle, or the bevel-pinions may be adjusted to drive one of the traction-wheels in a forward and the other in a rearward direction, 55 thus causing the frame of the vehicle to be turned or rotated in a horizontal plane. The vehicle may thus be very quickly and efficiently steered by manipulating one of the operating-rod 45. The steering may also be 60 effected by temporarily suspending the operation of the gearing on one side of the vehicle by manipulating one of the operating-rod 25.

It is obvious that means, such as hand-levers, may be provided for the purpose of 65 manipulating the operating-rod 25 and 45

and that other means, such as ordinary quadrants, may be provided for the purpose of retaining such levers at various adjustments. These devices, however, are well known in the art and have not been illustrated in the 70 drawings.

It will be evident from the foregoing description that in this improved machine the motor may be run continually in one direction, and that the power may be utilized 75 without stopping or reversing the operation of the motor to propel the vehicle forwardly or rearwardly, as may be desired, or to turn the vehicle while in motion, and that at the same time the vehicle may be stopped at any 80 place and the power be utilized for the purpose of driving stationary machinery. In the latter event the bevel-pinions 12 and 13 will be adjusted at an intermediate position where neither of said pinions will be in engagement with the bevel-gears 11. When stationary machinery is thus driven, one side 85 of the gearing may be permitted to remain idle, as will be readily understood.

Having thus described the invention, what 90 is claimed is—

1. In a motor-vehicle, traction-wheels having spur-gears connected therewith, shafts having pinions meshing with said spur-gears and provided at their inner ends with bevel-gears, and means for driving the latter including shafts supported independently for rotation, pairs of pinions slideable upon and rotatable with said shafts, and means for effecting simultaneous adjustment of the pair 95 of pinions upon each of said shafts independently of those upon the other shaft.

2. In a motor-vehicle, a pair of independent alined shafts, a driven shaft parallel thereto and having pinions at the ends thereof, spur-gears upon the independent shafts meshing with said pinions, friction means for connecting the spur-gears with the shafts upon which they are loosely mounted, a pair of traction-wheels, and means for transmitting 105 motion from the independent shafts to the respective traction-wheels.

3. In a motor-vehicle, a pair of independent alined shafts, a driven shaft parallel thereto and provided with pinions, spur-gears 115 upon the independent shafts meshing with said pinions, friction means for connecting the spur-gears with the shafts upon which they are loosely mounted, a pair of traction-wheels, and means for transmitting motion from each 120 of the independent shafts to one of the traction-wheels; said means including means for reversing the direction of rotation of said traction-wheels.

4. In a motor-vehicle, a frame, a pair of 125 independent alined shafts, spur-wheels upon said shafts having band-wheels formed integral therewith, friction means for connecting said wheels with the shafts upon which they are loosely mounted, a driven shaft, and 130

pinions upon said shaft meshing with the spur-wheels upon the independent shafts.

5. In a motor-vehicle, a pair of independent alined shafts, combined spur and band wheels mounted loosely thereon, clutch means for connecting said wheels with their respective shafts for rotation, a driven shaft having pinions meshing with the spur-wheels, means for independently operating the clutch means of the two shafts, a pair of traction-wheels, and means for transmitting motion from each

of the independent alined shafts to one of the traction-wheels; said means including mechanism for reversing the direction of rotation of said traction-wheels.

15 In testimony that I claim the foregoing as my own I have hereto affixed my signature in the presence of two witnesses.

CHARLES STUMMA.
